UNITED STATES PATENT OFFICE

97,410

DESIGN FOR A COMBINED CASKET LUG AND HANDLE

Gustav C. Pahlow, Galesburg, Ill., assignor to
Victor Casket Hardware Company, Galesburg,
Ill.

Application February 21, 1935, Serial No. 55,528

Term of patent 7 years

To whom it may concern:

Be it known that I, Gustav C. Pahlow, a citizen
of the United States and a resident of the city
of Galesburg, county of Knox, and State of Illinois,
have invented a new, original, and ornamental
Design for a Combined Casket Lug and
Handle, of which the following is the specification,
and reference being had to the accompanying
drawing, forming a part thereof.

Figure 1 is a front view of a combined casket
lug and handle, showing my new design; and
Figure 2 is an end view.

I claim:

The ornamental design for a combined casket
lug and handle as shown.

GUSTAV C. PAHLOW.
